FIG. 5

FIG.6

FIG. 7

FIG. 8

FIG. 1 is a side elevational view of a bicycle, showing my new design in the embodiment of a girl's bicycle;

FIG. 2 is a side elevational view thereof on an enlarged scale;

FIG. 3 is a top plan view thereof;

FIG. 4 is a front elevational view thereof;

FIG. 5 is a side elevational view of a bicycle showing my new design in the embodiment of a boy's bicycle;

FIG. 6 is a side elevational view thereof on an enlarged scale;

FIG. 7 is a top plan view thereof; and

FIG. 8 is a front elevational view thereof.

The dominant features of my design reside in the portions shown in full lines. The portions shown in broken lines are omitted from FIGS. 2, 3, 4, 6, 7, and 8 for convenience of illustration.

This application is a continuation of applications D. 66,073, filed July 26, 1961, and D. 66,268, filed August 9, 1961.

I claim:

The ornamental design for a bicycle, substantially as shown and described.
